AEROLOGICAL INSTRUMENT

Constantin P. Yaglou, Boston, Mass.

Application June 28, 1935, Serial No. 28,851

3 Claims. (Cl. 73—151)

This invention relates to air conditioning, and more particularly, to apparatus for measuring and controlling factors affecting human comfort.

5 Approximately eighty per cent of the body surface of the average person, when conventionally attired, is covered by an aerial envelope formed between the skin and the outer clothing. The 10 temperature of this aerial envelope increases progressively from about 84 degrees F. between the outer two layers of clothing, to about 96 degrees F. at the surface of the skin under the clothing. In order that a person may feel comfortable, it is essential that the temperature of 15 this aerial envelope remain substantially constant in summer and winter. When the temperature of this envelope drops appreciably, the sensation of cold is experienced, and when it rises, the sensation of warmth is experienced. The 20 temperature of this aerial envelope is dependent upon heat transfer between the body and its surroundings. When heat is dissipated from the body at a rate equal to that at which it is generated by the metabolic processes, the temperature of the air space between the outer two layers of clothing approximates 84 degrees F., and the individual will feel comfortable.

The dissipation of bodily heat is effected mainly by radiation and convection. Evaporation is 30 usually a minor factor, although when the air is uncomfortably warm, it plays an important emergency cooling role. The rate of heat loss by radiation depends entirely upon the difference between the temperature of the body surface and the mean surface temperature of the surrounding walls and objects. The rate of heat loss by convection depends upon the temperature difference between the body and the surrounding air, and upon the rate of air motion over the 35 body. The loss by evaporation is largely dependent upon sweat gland activity, relative humidity, and air movement. The sweat gland activity, in turn, is controlled by external temperature and the degree of physical activity.

40 The conventional dry bulb thermometer does not provide a true index of warmth or of the temperature of the aerial envelope surrounding the body, for it is substantially unaffected by radiant heat, while the temperature of the aerial envelope is affected greatly by radiant heat. Thus, a person in a room in which there are relatively cold walls and windows may feel cold, although the air in the room is at 70 degrees, due to radiation of heat from his body to the cold walls and 45 windows. Conversely, a person in a room in which the thermometer indicates a temperature of 60 degrees may feel entirely comfortable, or even uncomfortably warm, if he is subjected to the radiant heat rays of the sun, a radiator, or 50 other warm object. The standard dry bulb ther-

5 mometer is not at all affected by air motion, and thus fails to indicate accurately the extent to which the body is cooled by convection. The effective temperature index also fails to indicate accurately the summated effect of radiation and 10 convection on the temperature of the aerial envelope surrounding the body because it does not take into account the effect of radiation and because it underestimates the effect of convectional currents of low velocity.

15 In the past, there have been devised instruments of various types for the purpose of ascertaining the relative comfort of various environments, and for studying the effectiveness of different methods of heating, ventilating and air 20 conditioning. All of the instruments heretofore in use have more or less serious limitations in principle and design, and are far from satisfactory. The best of them are needlessly complicated and expensive; and their readings are in 25 such form as to require interpretation.

30 Among the instruments which have been used in the past are the eupatheoscope and the eupathestat. Both of these instruments operate on the basis of a variable heat input and constant surface temperature. In the case of the human body, and in the case of applicant's instrument, however, the reverse holds true, i. e., the metabolism or heat input remains constant within the comfort zone, but the surface temperature of 35 clothing and the aerial envelope temperature vary according to external conditions. In operation, the eupatheoscope and eupathestat either overcompensate or undercompensate for radiation and convection. For example, let us assume that a certain environment lowers the surface and aerial envelope temperature of the body two degrees. Heat loss from the body will then take place at a temperature two degrees lower than the surface temperature of the eupatheoscope, because the surface temperature of this 40 instrument is automatically kept constant regardless of the variations in external conditions. Since the heat loss by radiation varies as the fourth power of the absolute temperature of the radiating source, considerably more heat will be lost from the eupatheoscope than from the human body under identical external conditions, and if a eupathestat is used to control the room temperature, it is apt to cause overheating. 45 The error is in the opposite direction in warm 50 environments.

55 Furthermore, the eupatheoscope and eupathestat require measurement and control of surface temperatures. This procedure is complicated and expensive, requiring the use of involved auxiliary equipment. Moreover, these instruments cannot be used to advantage in practical installations in the air conditioning field, being outside the scope of the layman. Further,

they cease to function when the temperature exceeds 83 degrees, or when it is below the minimum temperature for which the heaters are designed. Applicant's instrument has no such limitation.

5 It is the general object of the invention to provide a simple apparatus for ascertaining the relative comfort of various environments and for determining to what extent radiation, convection and evaporation contribute to the maintenance of such conditions.

10 It is another object of the invention to provide apparatus for controlling atmospheric conditions in an enclosure responsive to variations in the 15 summated effect of radiation, convection and evaporation on the comfort of human beings within the enclosure.

15 It is another object of the invention to provide an improved anemometer.

20 It is another object of the invention to provide a novel comfort meter which is relatively simple, inexpensive and accurate.

25 In an elementary form, applicant's apparatus comprises two hollow metal or cloth spheres, one inside the other. Heat generated by a heating element within the inner sphere is dissipated by the outer sphere at the rate of 15.3 B. t. u. per square foot per hour, under standard environmental conditions (air and walls at 70 degrees F., 30 with substantially no air motion). This is approximately the average rate of heat loss from the surface of an average adult person by radiation and convection under comfortable air conditions. One or more thermometers are positioned in the air space between the spheres, to register the temperature thereof. The outer surface of the inner sphere is then comparable to the human skin. The air space between the two spheres is comparable to the aerial envelope between the 35 skin and the outer clothing, and the thermometers register the temperature between the outer two layers of clothing. The apparatus is subject to radiation and convection effects in approximately the same way as a human body in the same 40 position would be affected. Radiation and convection affect the temperature of the air space between the spheres approximately in the same way as they would affect the temperature of the aerial envelope between the skin and the 45 outer surface of the clothing. In warm summer weather, when perspiration often occurs, the outer sphere is wetted, and the air between the spheres is cooled by evaporation to an extent depending upon the relative humidity and air movement. 50

55 Under such conditions, the instrument is made to dissipate heat at the rate of 20.5 B. t. u. per square foot per hour, by adjusting the resistance of the heating element. This rate of heat dissipation represents the total heat loss from the 60 human body when at rest, by radiation, convection and evaporation.

Thus, applicant provides an apparatus which substantially reproduces the thermodynamic functions of the human body, and which is 65 affected by external conditions in substantially the same way as the human body is affected by them.

A feature of the invention resides in the 70 provision of a thermoresponsive element or elements within the air space between two containers for controlling atmospheric conditions externally of the apparatus responsive to variations in the temperature of said air space.

75 A further feature of the invention resides in

the provision of a simple means for measuring air velocities.

Other objects and features of the invention will be more apparent from a consideration of the following specification, to be read in connection with the accompanying drawing, in which

5 Fig. 1 is a cross-sectional view of one embodiment of the invention;

Fig. 2 is a longitudinal section through another form of the invention in which cylinders 10 are substituted for the spheres of Fig. 1;

Fig. 3 represents a section on the line 3-3 of Fig. 2;

Fig. 4 illustrates the application of the invention to the control of heating means;

Fig. 5 illustrates a modified form of the invention; and

Fig. 6 diagrammatically illustrates the application of the invention to the control of remote indicating means.

Referring to the drawing, a sphere 10 is positioned within a somewhat larger sphere 11. These spheres may be of heat conducting material, such as copper or aluminum, or may be made of cloth fabrics on wire frames. The outer 25 sphere is preferably blackened, on the outside. A heating element 12 is positioned within sphere 10. Element 12 is preferably a variable electrical resistance, supplied with electrical current from any suitable source through leads 13, which are carried through and insulated from spheres 10 and 11 by conduit 14, which also retains the spheres in spaced relation. Thermometers 15 are positioned in the air space 16 between the spheres to register the temperature thereof. The 30 stems of the thermometers 15 are preferably carried by small air tight conduits 25 extending through sphere 11. Instead of glass thermometers, thermocouples or resistance thermometers may be used for automatic registration of 35 temperature or control thereof.

Applicant prefers to utilize as the sphere 10 a standard 4 1/2" ball cock, and as the outer sphere 11 a standard 6" ball cock. The heating element 12 has two graduated stops at b and c. Section ab has a resistance of 2010 ohms, and section ac, a resistance of 3440 ohms. The contact point d is normally at c, except when the outer sphere is wetted in hot weather, when contact d is moved to b. When heating section ac is connected to a current source of 110 volts, the heat loss from the outer sphere approximates 15.3 B. t. u. per square foot per hour, the average rate at which heat is dissipated from the body surface of an adult by radiation and convection under comfortable conditions. When heating section ab is connected to an electrical source of 110 volts, the heat loss from the outer spheres is at the rate of 20.5 B. t. u. per square foot per hour, the average rate at which is dissipated from the body of an adult by radiation, convection and evaporation. It is apparent that spheres of other sizes may be used in conjunction with suitable heating elements without departing from the spirit of the invention.

Under standard environmental conditions, the average temperature between the outer two layers of clothing and hands varies between 82 and 86 degrees. The air between the outer two layers of clothing is most sensitive to and its temperature is most indicative of changes in atmospheric conditions affecting human comfort. It may be assumed that under standard conditions of comfort, the temperature of this air

space will be approximately 84 degrees. Therefore, thermometers 15 are so positioned within air space 16 that, when the apparatus is subjected to standard environmental conditions, they register 84 degrees.

In the triple globe thermometer illustrated in Fig. 5, thermometers 15 are so positioned in the air space 16a as to register 84 degrees when the apparatus is subjected to standard environmental 10 conditions.

The thermometers 15 usually give identical

vary in response to the same changes in radiation, humidity, ambient temperature and air movement. It will be seen, therefore, that applicant's apparatus constitutes a comfort meter, integrating the effects of the various factors affecting human comfort, and indicating the result by means of a thermometer inside the aerial envelope. The following table is a chart comparing applicant's apparatus with a conventional dry bulb thermometer, as an indicator of comfort under various environmental conditions.

Heated globe thermometer temperature in relation to sensations of warmth

15	Conditions of exposure	Glass thermometer temperature (2)	Applicant's device (3)	Difference (4)	Mean radiation-convection temperature (5)	Sensation of warmth (6)	15
20	Sitting near window, 2' from cold glass. Window shut. No sun-shine, radiator off. Room heated and ventilated mechanically. 6' above floor level, close to feet of observer. Sitting 8" away from a 10" desk fan.	70.7 67.3 77.1	78.9 74.6 82.3	8.2 7.3 5.2	64.9 60.6 68.3	Cold and drafty. Cold feet and drafty. Cool to cold.	20
25	Center of expt. room, 7 subjects, airflow 210 c. f. m. Center of room, window open 1", door open 9' from a wood fire in front of a fireplace.	74.4 74.5 67.2	85.8 85.5 85.3	11.4 11.0 17.7	71.8 71.5 71.3	Very comfortable. Do. Most comfortable and pleasing. Body perfectly comfortable. Feet cold.	25
30	Outdoors in clear sunshine. Snow on ground. Mild breeze (75-100/min.).	45.0	84.2	39.2	70.2		
30	Sitting in sunshine by window sill of expt' room. Window closed, radiator off. 6' from a wood fire in front of fireplace.	73.9 72.0	87.7 95.0	13.8 23.0	73.7 80.0	Warm. Too warm; slight perspiration.	30

readings. When, however, the apparatus is subjected to the action of radiant heat rays striking the outer sphere proximate one or the other of the thermometers, there is an appreciable difference in the thermometer readings. Similarly, when a draft strikes the outer sphere proximate 40 one of the thermometers, a drop in the temperature indicated by the thermometer will result from the greater heat transfer by convection from the outer sphere, due to the increased velocity of air passing in contact therewith. For 45 studying the directional effects of radiant energy and air motion, it may be desirable to use additional thermometers, such as 15a, to give readings at points 90 degrees apart.

The temperature of air space 16 and the surface temperature of sphere 11 are affected by the temperature of the air surrounding the apparatus, by radiation and by air movement. However, these temperatures are not affected by the humidity of the atmosphere surrounding the apparatus. At high temperatures, when the body is covered with perspiration, the amount of cooling due to evaporation is considerable. In such cases, accurate reflection of conditions by the thermometers may be assured by covering the 50 outer sphere with a tight-fitting moist cloth 17 dipping in a pan 18 containing water and by decreasing the resistance of the heating element as above described. It is to be understood, of course, that a dry or moist cloth may be used 55 at all times, if desired, and it may cover the sphere in part or in whole.

In operation, the apparatus will be placed on a table or attached to a wall in such a position that it is subjected to the same conditions as 60 the occupants of the room. The temperature indicated by the globe thermometers will vary, responsive to changes in radiation, humidity, ambient temperature and air movement, in approximately the same way as the temperature of the 65 aerial envelopes surrounding the occupants will

Thus, in the presence of radiant heat, sun rays or air movement, the temperature registered by the conventional thermometer bears little or no relation to the sensation of warmth or cold experienced by the observers. On the other hand, the readings of the globe thermometer correspond very well with sensations of comfort. Regardless of variations in air movement or radiant energy, the globe thermometer registered between 82 and 86 degrees, approximately, when conditions were comfortable. When cold was experienced, the globe thermometer registered below 82 degrees, and when the sensation of warmth was experienced, the globe thermometer registered 86 degrees or more.

Column 5 of the table gives the mean radiation-convection temperature of the environment. This is the temperature which an ordinary thermometer would register if it were possible for it to indicate the integrated effect of air temperature, positive radiation and convection, less that of negative radiation and convection. The readings of column 5 are obtained by subtracting 14 degrees from the readings of the applicant's device. The value of 14 degrees represents the difference between 84 degrees and 70 degrees, or the excess of globe temperature over air temperature in still air at 70 degrees with the walls and air at the same temperature. When the readings of the globe thermometer are transformed by subtraction of this factor, it will be seen that, as indicated in column 5, comfortable temperatures fall between 70 and 72 degrees, cold ones under 65 68 degrees, and warm ones over 72 degrees. These values are well in accord with American standards of comfort. If desired, of course, the scales of the thermometers 15 may be so calibrated that 70 they reflect temperatures of applicant's device corrected by subtraction of the 14 degree factor to read directly in familiar terms. Thus, there will be no need to interpret the readings of thermometers 15 and no need to depart from the lay- 75

man's concept that comfortable heating is indicated by thermometer readings between 70 and 72 degrees.

Instead of the two spheres of Fig. 1, the instrument may be constructed of two hollow cylinders, 23 and 24, as indicated in Figs. 2 and 3, the outer cylinder having a ratio of area to volume comparable to that of the human body. This form of the invention possesses a slight superiority over the spherical form when used as a comfort meter. However, its operation is affected by the direction from which air currents or radiant energy reach the cylinder, since the projected area of the cylinder is not the same in all directions, as in the case of the sphere. Hence, the cylindrical form of the invention is not as satisfactory as the spherical apparatus for measuring radiation or air movement. Vertical mounting is preferred.

20 Applicant's apparatus may be utilized for controlling the temperature of an enclosure as indicated in Fig. 4. The thermoresponsive element 19 is positioned in air space 16 in precisely the same manner as thermometers 15. Element 19 responds to variations in temperature in the air space 16, and through suitable control apparatus of any desired type, as indicated at 20, may, for example, operate valve 26 to control the admission of steam through pipe 27 to the radiator 28 25 heating the enclosure. While applicant illustrates his invention as controlling the admission of steam to a radiator, the invention is adapted to be used in conjunction with air conditioning systems of any desired type. For example, applicant's apparatus might be utilized to control the amount of conditioned air admitted to a conditioned enclosure, the admission of air to or the bypassing of air around an air washer, the temperature and supply of a heating or cooling agent, 30 etc.

40 Since there are well-known various forms of apparatus including thermo-responsive elements and means remote from said elements for indicating the temperature affecting said elements, or for controlling valves, dampers or the like, for controlling the temperature or other characteristic of the atmosphere affecting said elements, no detailed description or illustration of such arrangements is deemed required here, it being understood that any of these arrangements may be used in conjunction with the thermo-responsive element of applicant's apparatus as herein described. One of these well-known remote indicating and/or controlling systems, for example, is the "Fullscope" apparatus manufactured and widely marketed by the Taylor Instrument Company. Brown Instrument Company and other manufacturers also manufacture and widely sell such apparatus. Fig. 6 illustrates the application of the invention to the control of such remote indicating means. Thermo-responsive element 15b is positioned between containers 10 and 11 and, through a suitable control line 29 of any desired type (as, for example, a pressure-transmitting tube), controls remote indicating means 30.

45 In addition to use as a comfort indicator, the heated globe provides a highly satisfactory means of measuring air velocities, particularly low air velocities, for the measurement of which no satisfactory instrument has been available heretofore. The operation of the apparatus as an anemometer is based upon the principle that as the velocity of air contacting the apparatus increases, the globe temperature tends to fall, due

5 to increased heat loss by convection. The relation between temperature of the globe and air velocity is expressed by the formula:

$$tgs - tg = K\sqrt{V}$$

where

tgs =temperature of globe in still air.

tg =globe temperature in moving air.

K =calibration constant.

V =air velocity in feet per minute.

10 The globe temperature in still air (tgs) is given by the equation

$$tgs = a + bta$$

where

a and b =instrumental constants and

ta =air temperature.

15 When used as an anemometer, the outer sphere is preferably one to three inches in diameter and plated with cadmium to eliminate as much as possible the influence of radiant heat.

20 The heat input to the globe anemometer is varied according to the desired sensitivity and velocity of air to be measured. The higher the sensitivity and the higher the air velocity, the greater the heat input. By means of such an instrument, it is possible to measure air velocities within a fraction of a foot per minute by simply recording the temperature of the air and the temperature of the globe. To insure accurate air velocity determinations, care should be exercised to keep the apparatus at least 10 feet from radiators, cold walls, or the like. If this is not possible, the air velocity may be computed from the heat balance equation of the instrument, given below.

25 As heretofore described, the apparatus may be used to indicate the summated effect of radiation and convection. Often, however, it is necessary in problems of air conditioning to separate radiation from convection and to estimate the effect of each of the factors involved, such as air temperature, air movement, mean radiation intensity, and the mean temperature of the surrounding surfaces. The heated globe affords a suitable means for determining these factors individually. The heat balance equation of a 6" blackened globe may be written as follows:

$$12.0 = 0.95 \times 1.72 \times 10^{-9} \times 0.785(Ts^4 - Te^4) + (K + K_1\sqrt{V})(tg - ta)$$

where

12.0=heat loss from a 6" globe in B. t. u. per hour=15.3×0.785.

0.785=surface area of 6" globe in square feet.

0.95=emissivity of blackened globe.

1.72×10⁻⁹=value of Stefan's constant, expressing radiation in B. t. u. per square foot per hour.

Ts =absolute temperature of globe surface.

Te =mean absolute temperature of surrounding surface.

K and K_1 =convection coefficients determined experimentally in an insulated windowless chamber with air and walls at the same temperature.

V =velocity of air in feet per minute.

tg =globe temperature in degrees F.

ta =air temperature in degrees F.

10 The first expression on the right of the equation represents the heat loss by radiation from the surface of the globe according to the Boltzman Stefan law. The second expression represents the heat loss by convection. The sum of the two

is always equal to the heat equivalent of the electrical input to the globe (12.0 B. t. u. per hour) regardless of environmental conditions.

This heat balance equation finds many practical applications in problems dealing with comfort under various conditions of air temperature, radiation, and air velocity. For example, it may be required to find the air temperature necessary to produce comfort in rooms in which the mean radiation temperature (Te) of the surrounding walls, glass, ceiling and floor is considerably above or below the usual values. Te may be computed from data given in the Guide of the American Society of Heating and Ventilating Engineers.

15 $Ts = c + d (tg + 460)$

where

c and d are instrumental constants expressing the relationship between tg and Ts .

20 For a double globe 6" in diameter $c=50.4$ and $d=0.9$.

The value of tg for comfort is 84.0 (see table).

25 For still air, V may be taken as 10 feet per minute, or it may be determined by the use of a globe anemometer. The equation is then solved for ta by substituting the values of the known factors.

30 In rooms heated by radiant methods, it is necessary to know the mean radiant temperature Te to which the surrounding surfaces must be warmed in order to produce a comfortable condition at any desired temperature and air movement. The values of tg and Ts are as in the 35 previous example. By substituting the desired values of ta and V , the equation is solved for the unknown factor Te .

Knowing Te , the mean radiation intensity from the surrounding surfaces is:

40 $1.72 \times 10^{-9} \times Te \text{ B. t. u./sq. ft./hr.}$

The apparatus may also be used to determine the air velocity necessary to counteract radiant heat from furnaces or hot objects so as to produce a comfortable condition without sweating.

45 The instrument is particularly suitable for the study of drafts which are related to globe thermometer readings tg , or its equivalent ts .

A cylindrical globe is particularly suitable for

studying the heat insulating qualities of fabrics under practical conditions. The difference in the globe temperature readings with and without the cloth covering gives a direct measure of the insulation afforded by various types of clothing under various conditions of temperature, humidity, wind, radiation, etc.

In the practical use of the globe thermometer as a comfort meter or as an anemometer, records of comfort and/or air velocity may be obtained at any distance away from the instrument by utilizing thermocouples instead of the glass thermometer inside the globe and carrying the wires to registering or recording mechanism (galvanometer, potentiometer, etc.) at any convenient point. Such applications are particularly useful in theatres, and large public and industrial buildings where the air conditions are controlled from a remote central room.

Since certain changes in the invention may be made without departing from its scope, it is intended that all matter contained in the above description or shown in the accompanying drawing shall be interpreted as illustrative and not in a limiting sense.

I claim:

1. In an apparatus of the character described, a plurality of containers of different sizes, said containers being nested within each other in spaced relationship, means for heating the smallest of said containers, and means for measuring the temperature between two of said containers.

2. In an apparatus of the character described, a first hollow container, a second hollow container positioned within and spaced from said first container, means for heating said second container, and thermo-responsive means between said first container and said second container.

3. In an apparatus of the character described, a first hollow container, a second hollow container positioned within and spaced from said first container, means for heating said second container, thermo-responsive means between said first container and said second container, and means for wetting the exterior surface of said first container.
